[57] CLAIM

The ornamental design for data communications peripheral, as shown and described.

DESCRIPTION

FIG. 1 is a perspective view of a data communications peripheral showing our new design;

FIG. 2 is an enlarged top plan view thereof;

FIG. 3 is an enlarged front elevational view thereof;

FIG. 4 is an enlarged left side elevational view thereof;

FIG. 5 is an enlarged right side elevational view thereof;

FIG. 6 is an enlarged rear elevational view thereof;

FIG. 7 is an enlarged bottom plan view thereof;

FIG. 8 is a perspective view of a second embodiment of our design;

FIG. 9 is an enlarged top plan view thereof;

FIG. 10 is an enlarged front elevational view thereof;

FIG. 11 is an enlarged left side elevational view thereof;

FIG. 12 is an enlarged right side elevational view thereof;

FIG. 13 is an enlarged rear elevational view thereof; and

FIG. 14 is an enlarged bottom plan view thereof;

The circular pattern is understood to continue over the entire unshaded area in FIGS. 3, 4, 5, 7, 10, 11, 12, and 14.
